UNITED STATES PATENT OFFICE.

SAMSON D. WRIGHT, OF CLEVELAND, OHIO.

COKE-QUENCHING CAR.

1,317,253.

Specification of Letters Patent. Patented Sept. 30, 1919.

Application filed August 21, 1916. Serial No. 116,081.

To all whom it may concern:

Be it known that I, SAMSON D. WRIGHT, a citizen of the United States, residing at Cleveland, in the county of Cuyahoga and State of Ohio, have invented certain new and useful Improvements in Coke-Quenching Cars, of which the following is a specification.

This invention relates to railway cars and more particularly to what are known as coke quenching cars. The object of the invention is to provide an improved coke quenching car whose inclined floor or bottom has extensions or lips projecting beyond the sides of the car, the upper one into close proximity to the retorts or ovens from which the coke is discharged into the cars, and the lower one arranged to discharge the coke at a point remote from the car body; which avoids loss of coke by dropping between the car and retort or upon the track; and which extensions or lips are removable so that the car can be trimmed down to a size coming within established railway clearance lines, whereby it can be shipped on its own wheels and not in knockdown condition, as heretofore.

Further objects of the invention are in part obvious and in part will appear more in detail hereinafter.

In the drawings, which represent one preferred embodiment of the invention, Figure 1 is a side elevation of one half of the car; Fig. 2 is an end view; Fig. 3 is a plan view of the car floor; and Fig. 4 is a section on the line 4—4, Fig. 3.

The car shown in the drawings comprises a suitable frame or body 1 supported on trucks 2 and consisting of an inclined floor or bottom 3, end walls 4 and a side wall 5 in which are doors 6 hinged at 7 and through which the material is discharged from the car. Said doors may be held closed by suitable means and may be operated by any suitable mechanism such as the links 9 connecting said doors to arms 10 on shaft 10^a provided with gears 11 operated by racks 12 on the rods of pistons controlled by the cylinders 13. When the doors are opened the material readily slides down over the inclined floor and out through the doorways.

The car bottom or floor is made up of a series of overlapping floor plates 15 bolted to each other and to transverse beams 16, 55 which may be channels, I beams or the like, attached to the car frame, and also con-

nected at their ends to channel members 17 extending longitudinally along the sides of the car and substantially from end to end thereof.

In Fig. 2, the dotted lines A represent the established railway clearance lines, beyond which the railways prohibit any projection of rolling stock traveling over the line. As will appear, the floor or bottom of these coke quenching cars should project beyond these clearance lines when in service at the coke plant, but the railway requirements prevent shipping such a car in assembled condition over the lines, which has made it necessary to ship the cars in knock-down state and erect them upon arrival at the plant.

In the present invention the lower edge of the car floor is provided with an extension or lip 18 whose upper surface is in the same inclined plane with that of the car floor and which extends outwardly beyond the clearance line A. This lip may extend continuously from end to end of the car or, as shown, may be broken up into separate sections opposite the several car doors. It consists of a number of floor plates whose inner upper edges are grooved at 19 to receive outwardly projecting flanges 20 on the adjacent inner floor plates, and one end edge of each of which is provided with a flange 20 to enter a recess of the next lip plate, all of the plates being attached to each other by bolts 21 through said flanges, as will be understood. The inner edges of the lip plates are also provided with depending flanges 22 which abut the channel 17 and are secured thereto by bolts 23.

The upper edge of the car floor is provided with a similar extension or lip 24 comprising floor plates 25 attached to each other and at their inner edges to the adjacent floor plates 26 by bolts 27, and also provided with depending flanges 28 bolted to the longitudinal channel 17. The end floor plates 25 also have bolted thereto triangular end plates 29 which may also be bolted to the adjacent permanent end plates 30 of the car body.

The lower extension 18 delivers the material from the car at a point remote from the body and beyond not only the track but also the clearance line A. The upper extension 24 extends beyond the clearance line 110 and into close proximity to the retorts or ovens from which the coke is delivered to

the car. Consequently no coke is lost by dropping down between the retorts and track or by scattering over the track at the discharge side of the car. Nevertheless both 5 lips or extensions may be removed from the car body by taking out the holding bolts, which trims down the car to the area prescribed by the railways and enables it to be shipped in practically completely assembled 10 form.

What I claim is:—

1. A coke quenching car, comprising a body and trucks therefor, said body having a floor inclined laterally of the car, and an 15 extension for said floor projecting beyond the railway clearance lines, said extension having its surface in the same plane as the surface of the floor and being rigidly secured to and removable from the car body.
- 20 2. A coke quenching car, comprising a body and trucks therefor, said body having a floor inclined laterally of the car to the discharge opening, a door closing said opening, and an extension for said floor outside 25 of said door and projecting beyond the railway clearance lines, said extension having its surface in the same plane as the surface of the floor and being rigidly secured to and detachable from the car body.
- 30 3. A coke quenching car, comprising a body and trucks therefor, said body having a floor inclined downwardly from one side of the car body to the other and toward a discharge opening, a door closing said open-

ing, and an extension for said floor comprising plates having flanges fitting recesses in the floor and thereby having its surface in the same plane as the surface of the floor, said extension projecting beyond the railway clearance lines and being rigidly secured to and removable from the car body.

4. A coke quenching car, comprising a body and trucks therefor, said body having a floor inclined laterally from side to side, the upper edge of said floor being below the upper edge of the body, and an extension for the upper portion of said floor, said extension having its upper surface in the same plane as the surface of the floor and extending beyond the railway clearance 45 lines and being rigidly secured to and removable from the car body.

5. A coke quenching car, comprising a body and trucks therefor, said body having a floor inclined laterally from side to side, 55 the upper edge of said floor being within the railway clearance lines of the car, ends for said body extending above the upper edge of said floor, and an extension for the upper portion of said body beyond the floor thereof, comprising a floor portion in the same plane as the floor of the main body 60 floor and end portions, said extension extending beyond the railway clearance lines and being rigidly secured to and removable 65 from the car body.

In testimony whereof I affix my signature.
SAMSON D. WRIGHT.
